Primary Examiner — Doris Clark(74) *Attorney, Agent, or Firm* — Womble Carlyle Sandridge & Rice, LLP(57) **CLAIM**

The ornamental design for a threshold deck clip, as shown and described.

DESCRIPTION

FIG. 1 is a top left perspective view of my new design with environmental elements;

FIG. 2 is a left side profile view of my new design with environmental elements, the right side profile being a mirror image thereof; and,

FIG. 3 is a detailed close-up view of the left side profile of my new design.

The views of the threshold deck clip not shown form no part of the claimed design. The dash-dot lines in the Figures immediately adjacent to the shaded area represent unclaimed boundaries of the design. The dash-dash lines elsewhere in the Figures refer to environmental elements only and form no part of the claimed design. The wavy break lines in FIG. 1 indicates indefinite length.
